UNITED STATES PATENT OFFICE.

HARRY I. SHOTWELL, OF WENATCHEE, WASHINGTON.

FISH-SCREEN.

1,080,488.

Specification of Letters Patent

Patented Dec. 2, 1913.

Application filed September 2, 1913. Serial No. 787,756.

To all whom it may concern:

Be it known that I, HARRY I. SHOTWELL, a citizen of the United States, residing at Wenatchee, in the county of Chelan and 5 State of Washington, have invented certain new and useful Improvements in Fish-Screens; and I do hereby declare the following to be a full, clear, and exact description of the invention, such as will enable others 10 skilled in the art to which it appertains to make and use the same.

This invention relates to fish screens and has for an object to provide a screen adapted for location at the head of an irrigating 15 ditch to prevent the passage of fish from the feeding stream into such irrigating ditch and to present improved means for clearing the screen of accumulated rubbish.

A further object of the invention is to 20 provide a plurality of screens mounted on a revolving frame with improved means for changing the said screens to present the opposite side to the action of the current at each revolution.

25 With these and other objects in view the invention comprises certain novel constructions, combinations and arrangement of parts as will be hereinafter more fully described and claimed.

30 In the drawings: Figure 1 is a view of the improved screen in side elevation. Fig. 2 is a view of the improved screen in end elevation. Fig. 3 is a sectional view through said screen taken on line 3—3 of Fig. 1. 35 Fig. 4 is a perspective fragmentary view showing a means for locking the screens in the rotating frame. Fig. 5 is a top plan view of the means for holding the rotating frame against rotation.

40 Like characters of reference designate corresponding parts throughout the several views.

The improved fish screen which forms the subject matter of this application is 45 adapted to be located at the head of an irrigating ditch, the head being indicated in the drawing by the flume consisting of the side boards 10 and bottom boards 11, it being understood, however, that the particular form of flume is immaterial to the present invention.

At the flume, posts 12 are erected in any approved manner depending upon the nature of the supporting structure, here shown 55 as using an underlying cross-timber 13 and braces 14, it being understood, however, that

these underlying timbers and braces may be varied as circumstances may make desirable.

Upon the posts 12 a shaft 15 is journaled free to rotate and carrying hubs 16. The 60 hubs 16 carry a main frame consisting of arms 17 and cross bars 18 whereby a four sided rigid frame is produced as indicated more particularly at Fig. 3. It will be understood that this frame just described is 65 all rigidly connected with the hubs 16 and rotates upon or with the shaft 15.

Upon the side bars 17 intermediate their ends shafts 19 are journaled, said shafts rotating with the main frame and carrying 70 screens 20. The screens 20 are mounted upon auxiliary frames 21 which are rigidly carried by the shafts 19 so that said screens upon said shafts are free to rotate with the main frame. The frames 21 are locked 75 yieldingly against rotation in the main frame by means of clips 22 secured to said frames, the construction being shown particularly at Fig. 4 and with spring locked members 23 carried by the main frames and 80 adapted to yieldingly engage said clips 22, such engagement being shown particularly at Fig. 4.

The shafts 19 carry pinions 24 rigidly secured thereto in position to engage segments 25 secured to the posts 12. The posts 12 are also provided with levers 26 pivoted at 27 as indicated at Fig. 5 with a tension spring 28 adapted to hold the said levers against the action of the main frame en- 90 gaging upon the side indicated by the arrow in Fig. 5.

In operation it will be assumed that the flow of the water is in the direction indicated by the arrow at Fig. 3 and that it engages against the lowermost screen 20. The water will pass through the screen practically without hindrance until the accumulation of trash and extraneous matter upon the up-stream side of the screen renders the 100 passage of the water difficult whereupon the water will back up to a certain extent upon the up-stream side of said screen and exert a pressure against the said trash covered screen which will cause the main frame to 105 rotate in the direction indicated by the large arrow in Fig. 2. Such rotation is resisted by the lever 26 and spring 28 which, however, will be overcome by the pressure of the water permitting such screen to rotate 110 one quarter of a revolution until the next arm engages against the lever 26 whereupon

the frame will be brought to a halt with the next screen in series in position to stop the passage of fish. At the same time the pinions 19 of the upper screen will engage 5 the segments 25 to cause a planetary rotation of the upper screen as indicated by the small arrow in Fig. 2 whereby the trash covered side on the screen which would otherwise be upward is turned down to permit 10 the trash to fall off and also to present the opposite side of the screen to the action of the water when it finally reaches the point of operation again to permit the passage of the water to clean the screen. In 15 other words, each time a screen is presented to the action of the water it has been reversed so that the current tends to clean the screen which had been covered with trash upon the preceding operation.

20 The rotation of the auxiliary frames carrying the screens is resisted by the locking member 23 engaging the clip 22 but such locking means is yielding and as the main frame is rotated with considerable force the 25 force is sufficient to remove the clip 22 from engagement with the lock 23 and the length of the segment is sufficient to rotate the screen a complete half revolution to bring the clip 22 at the opposite side of the screen 30 into engagement with the lock. It will thus be seen that both the auxiliary frames and the main frame are locked yieldingly against rotation by spring actuated locks but of such nature that they are overcome by the 35 force exerted to permit the movement of such frames in the directions indicated by their respective arrows.

While locks have been shown at Figs. 4 and 5 for locking the auxiliary frames and 40 the main frame it is to be understood that such locks are only illustrative and that any yielding lock may be substituted therefor within the scope of the present invention.

I claim:

45 1. In a fish screen, a main frame mounted to rotate; auxiliary frames mounted for planetary rotation upon the main frame; means to hold the main frame yieldingly against rotation; and means for imparting 50 movement to one of the auxiliary frames when the main frame is moved by the action of the water.

2. In a fish screen, a main frame mounted

to rotate; a plurality of screens mounted for planetary rotation upon the main frame; 55 means to lock the main frame yieldingly against movement; means to lock the auxiliary frames yieldingly against movement; and means to rotate one of the auxiliary frames a half revolution at each quarter 60 revolution of the main frame.

3. In a fish screen, a main frame mounted to rotate; screens mounted for planetary rotation upon the main frame; means to lock the main frame yieldingly against movement; 65 means to lock the screens against rotary movement; and means to rotate each of the screens a half revolution at each complete revolution of the main frame.

4. In a fish screen, a rotating screen carrying frame; and means to reverse the screens at each presentation to the water. 70

5. In a fish screen, a main frame provided with a plurality of radially extending frame sections; a plurality of auxiliary 75 frames journaled in the radial frames; screens carried by the auxiliary frames; means to hold the auxiliary frames and screens in planes normally radial of the main frame; and means to reverse each of 80 said auxiliary frames at each complete revolution of the main frame.

6. In a fish screen, a main frame having a plurality of radial frame sections; auxiliary frames mounted in the radial sections 85 and themselves normally positioned radially of the main frame; screens carried by the auxiliary frames; pinions carried axially by the auxiliary frames; a segment positioned in the path of movement of the pinions, said 90 segment being proportioned to rotate the pinion a half revolution; means to hold the main frame yieldingly against movement; and means to hold the auxiliary frames yieldingly against movement. 95

7. A fish screen comprising screens each rotatable about its own axis and all rotatable about a common axis, and means to rotate each screen once during each revolution about the common axis. 100

In testimony whereof I affix my signature in presence of two witnesses.

HARRY I. SHOTWELL.
